UNITED STATES PATENT OFFICE.

KARL MUSSBECK, OF MUNICH, GERMANY.

MEANS FOR PRESERVING OIL-PAINTINGS AND SIMILAR ART OBJECTS.

1,031,727.

Specification of Letters Patent.

Patented July 9, 1912.

Application filed October 9, 1911. Serial No. 653,705.

To all whom it may concern:

Be it known that I, KARL MUSSBECK, a citizen of Germany, residing at Munich, Bavaria, Germany, have invented new and Improved Means for Preserving Oil-Paintings and Similar Art Objects, of which the following is a specification.

This invention relates to means for preserving works of art such as oil paintings, water color paintings, graphic objects and similar articles from destruction.

Briefly stated the invention consists in furnishing the article to be protected with an envelop of nitrogen gas, and in providing a casing of peculiar construction which is adapted to contain said article and to be charged with said gas.

In the accompanying drawing: Figure 1 is a cross section of a case embodying my invention on line G—H, Fig. 2; Fig. 2 is a rear view of the case partly in section on line J—K, Fig. 1; Fig. 3 is a detail of the joint between the rim and front plate; Fig. 4 a modification of Fig. 3; Fig. 5 a front view partly in section on line E—F, Fig. 6, of a modification of the case; Fig. 6 a side view partly in section on line A—B, Fig. 5; Fig. 7 a detail on a reduced scale of the rear plate shown in Fig. 5; and Fig. 8 a detail of the filling nozzle.

My improved casing for preserving pictures comprises essentially a glass back plate a , a glass front plate b and an intermediate rim a^1 , that connects the plates along their bottom and sides, the parts being connected in an air tight manner by burnt mastic or otherwise. At their top, the inner sides of the parts, a , a^1 , b are ground and polished to form a seat for an oblong top piece d which is cemented or otherwise connected to the case after the picture P has been inserted. One side a^2 of the seat and the corresponding side of top piece d are preferably slightly chamfered to obtain sufficient pressure between the contacting surfaces for cementing, after the top piece has been properly fitted in position. The latter is further provided with a port u for the admission of nitrogen gas which port may be subsequently closed by a suitable glass plug and mastic. The front plate b is connected to the rim a^1 either by a strip of mastic c as illustrated in Fig. 4 or by fusion as illustrated in Fig. 3. The painting or other object of art is held in position and simultaneously protected against shocks,

etc., by a cushioning strip y , which also serves to space the painting from the front plate b .

Means may be provided for automatically regulating the pressure within the casing so as to conform to the atmospheric pressure. These means consist of a receptacle e secured to back plate a and divided into two mercury compartments e^1 , e^2 by means of an intervening partition e^3 . Compartment e^1 communicates with the atmosphere by a vent q , while compartment e^2 communicates with the interior of the casing by a duct q^1 provided with an asbestos screen t . The compartments e^1 , e^2 also communicate with each other by a tube e^4 which is provided with cocks g and opens into compartments e^1 , e^2 by flaring mouths f . The mercury charge contained in both compartments and in tube e^4 will upon an increase of atmospheric pressure fall in compartment e^1 and rise in compartment e^2 so as to effect a corresponding increase of gas pressure within the casing. When the atmospheric pressure sinks, the operation is reversed as will be readily understood. The cocks g are always open, excepting when the casing is transported or laid down flat.

In Figs. 5—8, the casing is shown to be made of metal with a glass front b which is fitted to a flanged metal rim b_1 . The latter is connected to a thin metal back plate e_1 having strengthening stays d_1 , e_1 . The corners of the case are reinforced by angle pieces g^1 secured to the rim and back plate. A rubber or similar band k_1 accommodated within a recess b_2 of rim b_1 straddles the edge of glass plate b and provides an air tight closure while it simultaneously permits an independent expansion or contraction of the parts b , b_1 . The picture is held in position by springs p_1 abutting against the upper rim b_1 of the casing. A frame m_1 of angular cross section straddles the corner of the rim b_1 and is secured thereto by screws n_1 , so as to bear against packing k_1 and thus insure a tight joint at the edge of plate b . Each filling aperture for the nitrogen is provided with a threaded sleeve q_1 that contains a rubber plug r_1 placed between a pair of metal disks v_1 , u_1 . A cap t_1 engaging sleeve q_1 will when screwed down so expand plug r_1 that a tight closure is effected.

By the use of the nitrogen envelop, the destruction of the painting through damp-

ness, the oxygen of the air and similar agents is obviated, exsiccation, photo-oxidation and the highly objectionable darkening of the colors is prevented, while at the same time the visibility and harmony of the picture together with the light effects are in no way impaired.

I claim:

10 A device of the character described, comprising a casing adapted to contain a painting or similar object of art, a glass plate, a packing extending over and around the edges thereof, an angular frame that strad-

dles the corner of the casing and bears against the packing, means for securing said frame to said casing, whereby the packing is compressed, and a gas tight joint is formed between the casing and plate, and a charge of nitrogen gas within the casing.

15 In testimony whereof I hereunto affix my signature in the presence of two witnesses.

KARL MUSSBECK.
